UNITED STATES PATENT OFFICE

HERMAN L. STRONGSON, OF NEW YORK, N. Y., ASSIGNOR TO BERNARD D. COLEN, OF
NEW YORK, N. Y.

QUICK BREAK PLUG CONNECTER

Application filed November 14, 1930. Serial No. 495,705.

This invention relates in general to quick break plug connectors.

One of the objects of this invention is the provision of a plug connector such as is used for connecting household electrical appliances in circuit which is so constructed as to effect a rapid snapping break in circuit when the plug is removed from the appliance.

A further object of this invention is the provision of terminal receiving clips mounted for movement against the reaction of a spring so that the clips are snapped from the terminal of the appliance as the plug is removed.

A still further object of this invention is the provision of an apparatus of this type which is relatively cheap in construction, exceedingly simple in structure and adapted to cheap and rapid manufacture in quantity.

These and other objects as will appear from the following disclosure are secured by means of this invention.

This invention resides substantially in the combination, construction, arrangement and relative location of parts, all as will be set forth in greater detail hereinafter.

Referring to the drawing;

Figure 1 is an outside plan view of the device;

Fig. 2 is an interior view with half of the casing removed;

Fig. 3 is a cross-sectional view taken on the line 3—3 of Fig. 2;

Fig. 4 is a side elevational view of one of the clips.

Fig. 5 is a detailed view similar to Fig. 2 with some parts broken away showing the conductor wires connected directly to the clips.

This invention is directed to a plug connector of the type usually employed for connecting electrical appliances in circuit through a flexible conductor. The ordinary plug connectors as now made are subject to destructive sparking at the contact clips when they leave the terminal pins of the appliance. The prime object of this invention is the provision of a simple structure arranged to automatically effect a rapid, simple

operation between the clips and the terminals to reduce this destructive sparking.

Referring to the drawing, the plug connector comprises, as is usual, a two-part complementary insulating casing comprising the upper and lower halves 1 and 2. These parts are held together by screws 3 usually provided with nuts. Each half of the casing is provided with a semi-circular opening 4 through which the conductor wires enter the casing. Within recesses within the casing are the screws 5 to which the conductor wires are attached. In this invention there is also secured to these screws small coil springs 6. Each half of the casing is provided with parallel rectangular recesses 7 separated by a longitudinal wall 8 which forms part of each half of the casing. Slidably supported in these recesses are the spring clips 9 which are provided with screws 10 to which the other ends of springs 6 are attached. Each spring clip 9 is constructed of the form shown in Fig. 4. It is made of suitable spring metal, such as brass, and has a portion 15 which is transversely curved as is apparent from Fig. 3.

This portion 15 is complementary to a transversely curved portion 18, and the two portions are connected by the integral curved portion 16. The screw 10 passes through both legs of the curved portion with its head lying between the side wings 17. The ends of the portions 15 and 18 are curved outwardly as at 19. The terminal pins of electrical appliances are usually in the form of round rods with round ends. Thus when the plug is applied to the terminal pins the round ends engage the curved ends 19 of the clips to effect easy entry of the pins between the transversely curved portions 15 and 18. This construction insures rapid application of the plug and good contact between the clips and the terminal pins. When the plug is being withdrawn the frictional engagement with the pins and the clips causes springs 6 to be put under tension, so that the clips slide longitudinally forward so as to project beyond the casing. When the resistance of springs 6 overcomes the frictional resistance between the pins and the

clips, these springs snap the clips back into the casing and suddenly break the connection between the clips and the pins. As shown in Fig. 2, the normal position of the 5 clips is that they are fully withdrawn within the casing. In the construction shown, the springs 6 carry the current from screws 5 to the clips, but the invention, of course, is not necessarily limited in this respect, 10 since contact could be made through flexible connections directly to the clips. It is, of course, apparent that this invention is not limited to use with household appliances. The lower part 2 of the casing may be provided with longitudinal recesses 20 of the proper length into which the lower ends of screws 10 slidingly fit. With this arrangement the sliding movement of the clips may be limited by engagement between the ends 15 of the screws 10 and the slots or recesses 20. These recesses are provided so that if occasionally the clips have a tendency to grip the terminal pins of the appliance too greatly, the springs 6 will not be over-stretched and the clips will not be pulled 20 too far out of the casing. These recesses do not interfere with the quick breaking action of the connector as they permit the springs 6 to act to snap the clips back into 25 the casing. Although in usual practice disconnection will occur exteriorly of the casing so that the heat of the spark will be easily dissipated, it is apparent that the casing can be made longer so that the break 30 will occur within the casing.

The modification shown in Fig. 5 is quite similar to the form of the device in Fig. 2, and although the recesses 20 are not shown in the form of Fig. 5 they can, of course, 40 be employed. The main distinguishing feature of the structure of Fig. 5 is that the wires 25 of the flexible cord pass through springs 6 and are mechanically and electrically attached to screws 10. The springs 6 are, of course, anchored to the casing by 45 springs 5 at one end and are secured to the screws 10 and the clips at the other end. With this arrangement the springs 6 do not carry the current as the conductors are directly connected to the clips 9. It is also 50 pointed out here that this invention is not limited to a two-part casing, nor is it limited to an insulated casing since a metal casing of suitable form could be employed with 55 insulating supports therein for the various parts. It is hardly necessary to point out that the conductors 25 must have sufficient slack to permit the movement of clips 9 in the form of the invention (Fig. 5) where the 60 conductors are directly attached to the clips.

From the above description, it will be apparent that this invention resides in certain features of construction which may be embodied in other physical forms without departure from the invention. I do not, there-

fore, desire to be strictly limited to the disclosure given for purposes of illustration, but rather to the scope of the appended claims.

What I seek to secure by United States Letters Patent is:

1. A plug connector of the type described comprising an insulating casing having recesses therein, a movable spring clip in each recess, a spring connected to each clip, and means for attaching each spring to the casing. 75

2. A plug connector of the type described comprising an insulating casing having recesses therein, a movable spring clip in each recess, a spring connected to each clip, and means for anchoring each spring to the casing, said anchoring means providing the means to which the conductor wires are attached to the plug. 80

3. A quick break plug connector of the type described comprising a two-part casing having recesses therein, a connecting clip movably supported in each recess, a spring attached to each clip, and means for anchoring the springs to the casing, said springs being the sole current conductors from the anchoring means to the clips. 85

4. A quick break plug connector of the type described comprising an insulating support, spring clips movably mounted on said support, said spring clips comprising continuous pieces of metal folded over to provide substantially parallel pin receiving portions, and coil springs attached to said clips and supports for resisting movement of the clips. 95

5. A quick break plug connector of the type described comprising a two-part insulating casing having recesses therein, pin receiving clips slidably mounted in said recesses, said pin receiving clips comprising continuous pieces of spring metal formed to provide complementary pin receiving portions of curved cross-section, a coil spring connected to each of said clips, and means for anchoring the coil springs to said casing. 100

6. A quick break plug connector of the type described comprising a two-part insulating casing having recesses therein, pin receiving clips slidably mounted in said recesses, said pin receiving clips comprising continuous pieces of spring metal formed to provide complementary pin receiving portions of curved cross-section, a coil spring connected to each of said clips, and means for anchoring the coil springs to said casing, said casing having an opening therein through which the connecting wires pass for attachment to said anchoring means. 110

7. A plug connector comprising a casing, spring clips slidably mounted within said casing, and resilient means for resisting the movement of said clips while permitting their projection exteriorly of the casing so that sparking at the clips when disconnection occurs takes place exteriorly of the casing. 125

8. A plug connector comprising a casing, 130

spring clips slidably mounted in said casing, springs for resisting the sliding movement of said clips, and current carrying conductors mechanically and electrically connected to 5 said clips directly.

9. A plug connector comprising a casing, spring terminal pin receiving clips slidably mounted in said casing, springs anchored to said casing and connected to said clips to resist their movement, and insulated current carrying wires passing through said springs and connected directly to said clips.

In testimony whereof I have hereunto set my hand on this 13th day of November, A. D. 15 1930.

HERMAN L. STRONGSON.
